UNITED STATES PATENT OFFICE

NORTON A. MEARS, OF CHICAGO, ILLINOIS, ASSIGNOR TO CHICAGO FORGING & MANUFACTURING CO., OF CHICAGO, ILLINOIS, A CORPORATION OF ILLINOIS

CLOSURE LATCH

Application filed April 17, 1930. Serial No. 444,887.

The invention relates to latches of the type employed in securing the movable cover of an automobile hood in closed position and has especial reference to that type of latch which is enclosed within the hood with an operating handle projecting exteriorly of the hood.

A general object of my invention is to provide a latch of novel and advantageous construction which consumes a small amount of space inside the hood cover, is capable of convenient operation and may be manufactured economically.

In carrying out my invention I employ a latch construction including a resilient lever fulcrumed on one of the two sections to be secured together, and providing a latch arm adapted for swinging movement into and out of engagement with an abutment or keeper on the other one of the two sections. With this in view, a further object of my invention is to provide a novel and effective means for operating the lever and for releasably holding the same in either latching or unlatching position.

Another object is to provide an operating means for the lever having a portion projecting to the exterior of the hood and operable by a substantially vertical sliding motion. The objects of the invention thus set forth, together with other and ancillary advantages are attained in the embodiment of the invention illustrated in the accompanying drawing and hereinafter more particularly described, it being understood that various changes in the construction herein employed may be made by those skilled in the art without departing from the spirit and scope of the invention as expressed in the appended claims.

Figure 1 of the drawing is a side elevational view of my improved latch as applied to the inside of an automobile hood.

Fig. 2 is a fragmentary vertical sectional view taken approximately in the plane of line 2—2 of Fig. 1.

Fig. 3 is a horizontal section taken approximately in the plane of line 3—3 of Fig. 1.

While the invention is not limited to use in connection with automobile hoods, it is

particularly applicable to such a use and it will therefore be described in that environment.

The latch as shown is applied to the inside of a hood of which 7 designates a portion of the movable hood cover one edge of which is arranged to overlap slightly a fixed member of the automobile 8. Mounted on the inside of the cover section is a latch supporting structure generally designated 9 comprising a base plate 10 and an overlying plate 11. The plate 11 has a bracket arm 12 formed integral therewith, with the major portion thereof spaced a short distance from the base plate 10 and overlying a pedestal 12^a upstanding therefrom. A pin 13 supported at its opposite ends in the bracket 12 and the pedestal 12^a constitutes a fulcrum for a lever 14 which is journaled between its ends on the pin. One end portion of this lever constitutes a latch arm 15 of a length such as to be swingable across the joint formed between the hood section and the fixed member of the automobile into engagement with an abutment 16 constituting a keeper projecting from the fixed member of the automobile.

The lever 14 is preferably formed from a heavy gage wire or rod of suitable resilient material which is bent to form in addition to the latch arm 15 an operating arm 17. The arm 17 has a portion 18 which extends substantially parallel to the latch arm 15 and forms therewith a loop the bight of which provides a bearing for the pin 13. A cupped washer 19 engaging the rounded end of the bent lever retains it against sliding movement relative to the pin 13.

The free end of the operating arm 17 is disposed substantially opposite the latch arm 15, and at this end the arm 17 has a portion 20 bent reversely from the portion 18 and having its free end bent to form an eye 21.

The means for actuating the lever through the medium of the operating arm 20 comprises an angular handle bar 22 having an inner upright stem 22^a pivoted at its lower end in the eye 21 of the operating arm 17, and a shank 22^b extending outwardly from the upper end of the stem through the hood cover.

The outer end of said shank is bent to form a suitable handle 23.

To permit the passage of the handle shank 22^b through the cover, the latter is provided with an elongated upright slot and the base 5 plate 9 has a registering slot cut therein. Thus a guideway 24 (Fig. 2) is formed for the handle shank. A guide for the stem 22^a is formed by a raised channel-shaped member 10 25 which may be formed integral with the plate 11.

The guideway 24 is of a length such that in the movement of the handle bar 22 from one extreme end of the guideway to the other the latch arm 15 is swung about its fulcrum 13 15 from an active position in engagement with the keeper 16 to a retracted position spaced a substantial distance inwardly from the free edge of the cover. In its lowermost position the handle shank 22^b is adapted to enter a lateral notch 26 (Fig. 1) at the lower end of the guideway 24 and opening thereinto so as to form in effect a bayonet slot. The notch 26 is formed in the cover section 7 and in the base plate 9.

The arrangement is such that the latch arm 15 is adapted to engage with the keeper abutment 16 just in advance of the movement of the handle bar downwardly far enough for the shank to enter the notch 26. Consequently as 30 the handle shank is moved into the notch, the lever, having its latch arm 15 engaging the abutment, is placed under tension.

Means is provided for yieldably holding the 35 handle bar 22 in the upper end of the guideway 24. This means comprises in the present instance a coiled contractile spring 27 having one end connected to the lower trunnioned end of the stem 22 and its other end 40 anchored to the base plate 10 in a position such as to draw the handle bar upwardly. Thus the latch arm 15 is held retracted from the keeper 16, with the handle 23 in position for convenient use as a means for lifting the 45 hood cover. In this connection it will be observed that the upper end of the guideway is engaged by the handle shank 22^b just before the stem 22^a of the handle moves into dead center relation to the operating arm 20, so 50 that a downward force applied to the handle is effective to swing the lever into engagement with the keeper.

In order that the latch may be effective to restrain the hood cover against outward 55 movement in a direction perpendicular to the fixed member of the automobile, the lower surface of the keeper abutment 16 is inclined upwardly and inwardly as indicated in Fig. 2 to form a cam surface 28. Since the latch 60 arm 15 is held under tension when engaging with this cam surface 28, the hood cover is drawn and held firmly in closed position. The keeper abutment 16 may be constructed 65 economically from sheet metal. Thus it may comprise a base plate 29 having integral with

opposite side edges thereof arms 30 which may be bent at their free ends into abutting relation to form the abutment.

It will be seen that I have provided a latch having an operating means, which through a simple and convenient manipulation is capable of swinging the lever to move the latch arm from active to inactive position and vice versa, and which is furthermore operative to hold the latch arm in either extreme position, 75 serving when the arm is in latching position to hold the two sections of the hood or other structure firmly together under tension.

I claim as my invention:

1. A latch for a closure member, comprising in combination, an abutment projecting from means defining the opening closed by the closure member, a lever fulcrumed on the movable closure member for rotation in a plane parallel to the member, and a handle bar journaled at one end in said lever to rotate the same and guided at the other end in said movable member for substantially vertical reciprocatory motion. 80

2. A latch for a closure member, comprising, in combination, an abutment projecting from means defining the opening closed by the closure member, a lever fulcrumed on the movable closure member for rotation in a plane parallel to the member, and a handle bar having one end journaled in said lever, 85 said closure having an upright guide adapted to receive the other end of the handle bar, said bar being operable to rotate said lever into or out of engagement with said abutment upon vertical motion of the bar in said guide. 90

3. In an automobile hood latch, the combination, comprising, an abutment projecting from a fixed member of the automobile, a lever fulcrumed on the hood cover for rotation in a plane parallel to the cover, a handle bar having one end journaled in said lever and the other end guided for substantially vertical movement, said bar being adapted to rotate said lever into or out of engagement with said abutment, and a spring operable to hold said lever in retracted position. 105

4. An automobile hood latch comprising, an abutment projecting from a fixed member of the automobile, a resilient member fulcrumed on the hood cover for rotation in a plane parallel to the hood and into engagement with said abutment, a bar journaled at one end in said lever, means for guiding the other end of the bar for substantially vertical movement, and a spring tending to hold said bar at the upper limit of its movement short of a dead center relation to said lever. 115

5. An automobile hood latch comprising, in combination, an abutment projecting from a fixed member of the automobile, a resilient lever fulcrumed on the hood cover for rotation in a plane parallel to the cover, means providing on the hood cover a substantially 120 125 130

- vertical slot with a horizontal enlargement at its lower end forming a bayonet lock, and a bar guided at one end for movement in said slot and journaled at the other end in said lever to rotate the same into engagement with said abutment, said bayonet lock being positioned to require flexing of the lever due to engagement with said abutment before said bar may be received in the lock. 5
6. A latch comprising, in combination with two parts to be connected in overlapping relation, an abutment on one of said parts, a resilient lever fulcrumed on the other part for rotation in a plane parallel therewith and providing a latch arm adapted for swinging movement across the overlapping joint between the parts into and out of engagement with said abutment, and a handle bar pivotally connected to said lever, the part on which the lever is mounted having an elongated guide in the plane thereof and said handle bar having a portion operable in said guide and extending to the side of the part opposite the side on which the lever is mounted. 15
7. A latch for an automobile hood cover and the like comprising, in combination, a resilient slightly flexible lever fulcrumed between its ends on the cover and having a latch arm at one end, a handle at the other end of said lever, a keeper stationarily mounted at one side of the cover, said lever being swingable substantially in the plane of said cover so as to move said arm into and out of engagement with said keeper, and means engaged by said handle in the latched position of the arm positioned to require distortion of said lever. 20
8. A latch for an automobile hood cover and the like comprising, in combination, a resilient lever fulcrumed between its ends on said cover and having a latch arm at one end and a handle at the other end, a keeper stationarily mounted at one side of the cover, said lever being swingable substantially in the plane of said cover so as to move said arm into and out of engagement with said keeper, and means for releasably holding the lever under tension in either its operative or its inoperative relation to said keeper. 25
9. A latch for securing the parts of an automobile hood in closed position comprising, in combination, an abutment on a fixed part of the automobile, a lever fulcrumed on the hood to be swung into engagement with said abutment, and an operator guided for rectilinear movement in the part of the hood supporting said lever to swing it into engagement with said abutment, said lever being yieldable to permit movement of said operator into latched position after engagement of the lever with the abutment. 30
10. A latch for securing the parts of an automobile hood in closed position comprising, in combination, an abutment on a fixed part of the automobile, a lever fulcrumed on the hood having an arm for engaging said abutment and an operating arm, a portion of said lever being yieldable to permit movement of one arm relative to the other, an operator having a pivotal connection at one end with the operating arm of said lever and guided at the other end in the part of the hood supporting said lever for substantially vertical rectilinear motion, and a lock for receiving said operator engaged only upon continued movement of the operating arm after engagement of said lever with said abutment. 35
